UNITED STATES PATENT OFFICE.

JOSEPH LINDEBURG, OF BROOKLYN, NEW YORK, ASSIGNOR TO UNDERWOOD TYPE-WRITER COMPANY, OF NEW YORK, N. Y., A CORPORATION OF DELAWARE.

FUME-DISPOSAL APPARATUS FOR WORKBENCHES.

Application filed October 8, 1923. Serial No. 667,430.

This invention relates to an apparatus in which typewriters, other machines and parts may safely be cleansed with volatile, inflammable liquids, such as alcohol or gasoline. It is constructed to comply with the rules of the fire departments in various localities, which, in some cases, require the exhaustion of the fumes with a minimum quantity of air per minute, and, in others, require a minimum mean velocity of air through the apparatus. Novel means are disclosed for efficiently collecting, exhausting and properly disposing of fumes created by the inflammable liquids within the apparatus, taking into consideration the natural properties of the generated vapors and other conditions arising during the cleansing operation.

The improved collecting means includes a novel shaped hood with a contracted upper portion having an auxiliary inlet to the exhaust at the highest point in the hood. The shape and construction of the hood are such that the rising vapors are completely and effectively withdrawn, and dead-pockets where such vapors might accumulate are eliminated.

Another novel feature in the design of the hood is the construction of the front opening with a head-plate formed from the rear enclosing side, extending down at the front of the opening. It is well known that flowing fluids tend to cling to the sides of the vessel through which they pass. This effect is especially marked in handling gases, vapors or fumes. The rising vapors cling to the sides of the hood near the edges of the front opening and tend to escape from the hood. To overcome this tendency, the head-plate is made to extend down over the upper side of the front opening, and has an arch-shaped edge which forms the upper edge of the front opening.

Another feature of the invention is the novel construction of the exhaust passage from the upper or auxiliary exhaust inlet to the main intake of the exhaust fan. This improved feature, instead of having the auxiliary exhaust inlet connect by a separate outside pipe to the main intake of the exhaust fan, as is usually the case, consists in partitioning, at the rear wall of the hood, a narrow portion of the interior thereof to form a separate passage. The upper opening of the passage forms the upper or auxiliary inlet and the lower opening connects

with the lower or main exhaust opening and with the intake of the exhaust fan.

An advantage of having a double passage for communicating the fumes in the hood with the conduit formed between the rear wall of the hood and the partition therein, is that fluids generating gases of different specific gravity may be used, such, for example, as gasoline and alcohol. Gasoline fumes are heavier than air, and therefore will tend to cling low over the work-top of the bench and will be drawn through the opening at the bottom of the hood, while alcohol fumes, being lighter than air, will rise to the top of the hood to be sucked into the opening at the top.

Another feature of the invention is to provide a baffle-plate at the lower edge of the partition to shield the lower or main exhaust inlet, so that no foreign matter, especially solid material, can accidentally get into the exhaust fan where impact with the rotating blades thereof might cause a spark or do other injury to the apparatus.

There is provided an electric light at the top of the housing or hood to illuminate the machine within the hood. Due to the fact that this hood may be used as a work-bench upon which the typewriters may be adjusted previous to being cleaned, there is provided novel means for controlling the light and the motor simultaneously. To this end there is provided a switch through which the light may be turned on or off while the motor is running, or the motor may be stopped while the light is on.

Another feature of the invention is the simple, compact and convenient arrangement of the electrical and mechanical parts to form the improved apparatus for the purposes disclosed.

Other features and advantages will hereinafter appear.

In the accompanying drawings,

Figure 1 is a diagrammatic front view of the apparatus.

Figure 2 is a diagrammatic side elevation of the same.

Referring to the drawings, the apparatus comprises a bench 10 having a dished metal-lined top 11, over which is fitted a metal hood 12. The hood 12 has a suitable opening 13 on one of the upstanding sides which gives access to the top 11 of the bench 10 on which the cleansing operation takes place.

The side of the hood 12 having the opening 13 therein will be designated as the front of the apparatus. The front opening 13 is suitably bound by an arc-top stiffening rim 5 13^a of circular cross-section. This construction gives the opening 13 a desirable smooth edge. It also allows means for connecting at the top edge of the opening 13 the head-plate 12^b formed from the rear upstanding 10 wall 12^a of the hood 12. The head-plate 12^b over the opening 13 is necessary to prevent rising vapors that cling to the sides of the hood, near the edges of the opening 13, from permeating outside of the hood 12. The 15 rear upstanding wall 12^a has its top portion sloping forward so as to shape the hood 12 to reduce the upper cross-sectional area and to eliminate the formation of dead-pockets in which the rising vapors would tend to 20 accumulate. The upstanding wall 12^a of the hood 12 has an inner partition 14, which, together with the side wall 12^a, forms an air-space 15. An upper or auxiliary inlet 16 to the air-space 15 is formed at the upper edge 25 thereof. The lower end of the partition 14 has a forwardly sloping baffle-plate 17, which is arranged to form a lower or main inlet 19 with an upstanding inner wall 18 mounted on top 11. The sum total of the areas of 30 the upper inlet opening 16 and the lower inlet opening 19 is made to be equivalent to the area of the fan inlet 20 of the exhaust fan 21. The exhaust fan 21 may be of the conventional types used for this class of 35 work.

A fully-enclosed, acid-proof, electric motor 32 may be directly connected to drive the fan 21. The motor 32 and exhaust fan 21 are suitably supported on the bench 10, as 40 on cross-beams 38.

The baffle-plate 17 at the lower end of partition 14 extends over to shield the lower inlet opening 19, as shown in Figure 2, so that foreign matter cannot accidentally get into 45 the fan 21 and cause a spark with the revolving blades thereof or otherwise cause injury to the apparatus. The hood 12 has an extension-hopper or conduit 22 downwardly depending from its rear side, which 50 leads into a box-like chamber 23. The latter is connected by suitable means to the fan inlet 20. The extension-hopper 22 has a front-extending bottom portion designed to offset the downward contraction of the hopper 22, where it joins chamber 23. The cross-sectional areas of the inlet and outlet 55 openings of hopper 22 are each kept equivalent to the area of the fan inlet 20, so that the losses, due to friction, of the flowing 60 fumes to the exhaust fan, are reduced to a minimum. The fan has an outlet 24 and attached thereto an exhaust pipe 25 which leads into the exhaust line 26. The latter 65 may be extended in a suitable manner to exhaust the fumes through some opening in the

wall of the building (not shown) to the atmosphere, or may be otherwise safely disposed of.

For assembling and cleaning purposes, a hand-hole 27 may be provided in the back of chamber 23, which may have a suitable closure, as sliding door 28. Standard fittings and motor are used in the electrical installation. The light and motor may be controlled individually, but, for simplicity, compactness and convenience, are preferably arranged as follows. The wires are enclosed in conduits designated as a whole as 29, and are fastened to the bench 10 by suitable means, as by clamps 30. A branch-fitting 31 in conduit 29 leads to the motor 32 through a conduit-pipe 33, and to the light 34, located within the hood 12, through conduit-pipe 35. The electrical supply connection is led to the apparatus from a suitable source (not shown), through conduit-pipe 37. Snap-switch 36, for controlling the light and the motor, is positioned at one side near the front of the apparatus, within easy reach of the operator. The switch 36 may preferably be of the conventional four-way type, which, for example, will, on successive operation, first start the motor 32; second, turn on the light 34 while the motor 32 runs; third, turn off the motor 32 with light 34 still burning; and, lastly, turn off the light 34. This cycle may be repeated as often as required, or the successive controls may be connected to give any other suitable cycles desired. Conduit-system 29, switch 36, light 34 and motor 32 are of the standard vapor-proof type, approved by the fire underwriters, and are readily obtainable from any dealer in electrical supplies.

When using gasoline for cleansing, the vapors created, which are heavier than air, do not rise, but remain close to the place where cleaning is being done. Therefore, the lower or main inlet 19 is arranged between the partition 14 and the rear wall 12^a, near the bottom of the hood 12, immediately above the work-top 11 of the bench 10. By this arrangement, most of the vapors may easily be drawn into chamber 23 and exhausted by the fan 21. The upper or auxiliary inlet 16 is arranged for the purpose of catching such vapors that escape the lower inlet 19. The amount of vapors to be taken care of by the auxiliary inlet 16 will vary with the room temperature and humidity of the air, and with the amount of stirring up of the air and vapors in the hood, in handling the machine during the cleansing operation. When using alcohol as a cleansing fluid the amount of vapors to be handled by the auxiliary inlet 16 is noticeably greater than when gasoline is used. The fumes created while cleansing in the improved apparatus, as herein disclosed, will be prevented from escaping except through the ex-

haust provided, and can be safely disposed of. The surroundings in which the operator works will also be kept practically free from obnoxious vapors.

5 Variations may be resorted to within the scope of the invention, and portions of the improvements may be used without others.

Having thus described my invention, I claim:

- 10 1. An apparatus for removing fumes from a work bench, some of the fumes being lighter and others heavier than air, comprising a hood having a front and a rear wall, the rear wall extending upwardly from the bench then forwardly over the bench and curved downwardly to an opening in the front of the hood, the front wall terminating within and near the top and bottom portions of the rear wall with a space intermediate 15 the walls extending across the top of the hood, means communicating with the bottom of the hood for sucking the fumes lighter than air over the top terminal of the inner wall downwardly between the walls and the 20 walls extending across the top of the hood, means communicating with the bottom of the hood for sucking the fumes lighter than air over the top terminal of the inner wall downwardly between the walls and the 25 fluid heavier than air down under the lower terminal of the inner wall and through the sucking means and a conduit for conducting the fumes away.

2. A safety apparatus for removing fumes 30 from a work bench comprising a hood having an inner and a rear wall and end walls, the rear wall extending upwardly and forwardly over the bench, then downwardly to an opening in the front of the hood, the inner wall extending from one end wall to the other of the hood and terminating near the top and bottom portions of the rear wall with a space intermediate the inner and rear walls, a second inner wall in the hood extending above the lower terminal of the first 35 mentioned inner wall, means for sucking the fumes over the top terminal of the upper inner wall and between the bottom of said inner wall and the top of the second inner 40 wall and through the sucking means, and a conduit for discharging the fumes at a distance from the hood.

3. A safety apparatus for use in cleaning typewriters and the like, comprising a shelf 45 dished on its upper surface to collect cleaning fluid and having a hood extending over the rear edge and ends of the dished portion with an opening at the front side of the hood, said hood having an outer and inner wall at its rear portion, the outer wall extending over the hood and down to the opening in front of the same, the inner wall of the hood terminating within the outer wall and near its top portion, said inner wall 50 also terminating above the dished portion of the shelf, a second inner wall extending upwardly over the ends of said dished portion and overlapping the lower portion of the first mentioned inner wall with a space between the overlapping inner walls and both

inner walls and rear wall, and means for sucking the fumes that rise to the top of the hood over the first mentioned inner wall and also sucking the fumes that tend to settle in the dished portion of the shelf upwardly 70 between the overlapping portions of the inner walls and means to convey the fumes to a distance from the hood.

4. A safety apparatus for removing volatile fumes while cleaning a typewriter or the like, comprising a shelf on which the apparatus to be cleaned is adapted to sit, a hood for enclosing the apparatus to be cleaned having an opening in its front wall, said hood having a conduit extending from its 80 upper portion, downwardly to its lower portion, and a branch conduit extending from above the shelf to the lower portion of the first mentioned conduit, a fan below the shelf communicating with both conduits and with 85 an outlet conduit whereby fumes may be drawn from the upper portion of the hood and from the lower portion thereof above the shelf down through the fan and out through the conduit.

5. A cleaning apparatus comprising a bench having a work table for supporting the apparatus to be cleaned and a fan beneath the work table, a hood comprising a 90 rear wall extending from the fan upwardly over the apparatus, and downwardly to an opening in the front of the hood, an inner wall spaced from the rear wall extending from the top portion of the hood and terminating above the table, a second inner 95 wall extending upwardly from above the table and then downwardly and terminating above the fan opening, there being a space between the rear wall of the hood and both the inner walls and between the inner walls, and a conduit leading from the fan whereby fumes may be sucked by the fan from the top of the hood and between the two inner walls downwardly through the fan 100 and discharged through the conduit.

6. An apparatus for use in cleansing typewriters and the like, where volatile fluids are used, said apparatus comprising a suitable work table, a hood over said work table for enclosing and confining fumes created during the cleaning operation, a duct having a lower opening and inclined upwardly from the work top through which most of the vapors are drawn from the hood, said duct being formed by a partition along the rear wall of the hood, another opening in said duct positioned at the top of the hood for catching the vapors that may not enter the first mentioned opening, means below the hood for exhausting and disposing of the fumes from both openings, and a baffle plate at the lower end of the partition positioned over the lower opening to guide against accidental passage into the exhausting means of foreign material that is 115 120 125 130

liable to produce a spark in the exhausting means.

7. A cleansing apparatus comprising an enclosure for confining fumes resulting from a cleansing operation, said apparatus including a power driven exhaust fan, the suction end in close communication with said enclosure for withdrawing the fumes from the enclosure, the communication between the fan and the enclosure comprising a main passage with two branches, one branch extending from the upper portion of the enclosure downwardly and the other from the lower portion of the enclosure first upwardly to prevent solid particles passing therethrough and thence join the other passage in a downward direction, the last mentioned passage merging into a closed chamber in front of the fan, and an exhaust outlet from the fan to conduct the fumes to a distance from the enclosure.

8. A cleaning apparatus comprising a bench having a work table thereon, a hood for enclosing and confining the fumes created during the cleansing process having an opening in the front upright wall of the hood to give access to the work table, a conduit at the rear of the hood having a main exhaust opening positioned close to the work top, said conduit extending first upwardly and then downwardly and through which most of the vapors may be withdrawn, a partition along the rear wall of the hood forming a passage between the partition and the rear wall of the hood, said passage extending over the upper portion of the hood for catching the vapors that rise and may not have entered the main lower inlet, a power driven exhaust fan below the work top, a chamber at the entrance end of the fan the rear wall of the hood extending down in front of said fan to form one wall of the chamber and of the passage from the upper portion of the hood and an outlet for conducting the vapors to the outside atmosphere from the fan.

9. A cleaning apparatus comprising a bench having a work-top thereon, a hood for enclosing and confining the fumes created during the cleansing process, having an opening in the front upright wall of the hood to give access to the work-top, a conduit at the rear of the hood having a main exhaust inlet opening positioned close to the work-top through which most of the vapors may be withdrawn, a partition along the rear wall of the hood forming a separated passage between the partition and the rear wall of the hood, an auxiliary inlet opening at the upper end of the passage for catching the vapors that may not enter the main inlet, a power-driven exhaust fan, a chamber connecting the conduit with the fan, suitable piping therefrom for conducting the vapors to the outside atmosphere, and a baffle-plate at the lower end of the partition positioned over the main inlet opening to guard against accidental passage of foreign material that is liable to cause damage and injury.

10. A bench having a work-top for cleaning typewriting machines and the like with volatile inflammable liquids, a hood for confining the fumes generated during the cleansing process, having an opening in the front wall to give access to said work-top, a partition parallel to the rear wall of the hood and spaced therefrom forming a conduit for carrying the fumes entering through an opening at the top, a comparatively low upstanding wall separated from the rear wall forming a passage and co-operating with the lowermost end of the partition to form a second opening higher than the work-top through which the vapors are also drawn into said conduit, and means for exhausting and disposing of the fumes, said means comprising a suction-fan operatively connected to said conduit by means of pipes having the same area as the combined areas of the two openings to eliminate frictional resistance within the conduit.

JOSEPH LINDBURG.
